DUPLICATING MACHINE

Fred M. Houshalter and Fred O. Weisman, Milwaukee, Wis., assignors to Ditto, Incorporated, Chicago, Ill., a corporation of West Virginia

Application July 25, 1935, Serial No. 33,100

14 Claims. (Cl. 101—133)

This invention relates to duplicating mechanism and particularly to means whereby master records made up from a plurality of separate strips or sheets may be assembled either side by side or in an overlapping relationship and applied to a duplicating mechanism to produce a composite copy which contains the material exposed on the several strips or sheets.

It is the purpose of the present invention to provide a device for assembling in parallel or overlapped relation a series of sheets or strips and positioning them during the assembly with relation to the printing bed of a duplicating machine so that they may be pressed down in contact with the duplicating band on the bed by the usual platen roller used in making copies.

It is a further purpose of this invention to provide a novel device of this character which may be readily attached to and removed from the printing bed of a duplicating machine without in any way interfering with the use of the machine with regular master sheets as may be desired.

Other objects and advantages of the invention will become apparent as the following detailed description progresses, reference being had to the accompanying drawings wherein—

Fig. 1 is a longitudinal sectional view through a duplicating machine showing the invention applied thereto;

Fig. 2 is an enlarged sectional view similar to Fig. 1 but illustrating the construction of the attachment more clearly;

Fig. 3 is a plan view of a flat bed duplicating machine showing the invention applied thereto;

Fig. 4 is a sectional view on the line 4—4 of Fig. 2; and

Fig. 5 is an enlarged sectional view on the line 5—5 of Fig. 1.

Referring now in detail to the drawings, the invention is shown as applied to a duplicating machine of the hectograph type having a flat printing bed. The stand of the machine is indicated at A and on this stand is the frame B of the machine which carries a printing bed D and has suitable guide means E for guiding a carriage C.

A duplicating band F is mounted on spindles G and H and passes over the printing bed D. The machine may have the usual standard margin bar M and a suitable moistening device such as indicated at R in Figs. 1 and 2 for maintaining the duplicating band in proper condition.

The structure so far described is well known in the art and will not be described further except in so far as it is necessary to bring out the func-

tion of the novel features comprising the present invention.

Original or master sheets used with the present invention are preferably provided along opposite edges with spaced holes. It is sometimes desirable to divide up the master records into strips and reassemble certain strips taken from different masters so that the information contained in the several strips may be reproduced in one complete copy.

Preferably, in so dividing the master records, each strip should have at least two holes at each end thereof.

The present invention provides means consisting of a pair of bars or plates 10 and 11 which are adapted to run lengthwise of the bed plate D and be arranged in parallel relation to each other. Each of the bars 10 and 11 carries a number of pins 12 spaced lengthwise thereof to correspond to the spacing of the holes provided in the master records. Pins 12 may be secured to their respective bars in any suitable manner such for example as that shown in Fig. 2 where each pin is provided with a reduced shank 13 that passes through the bar and is spread out as indicated at 14 to securely rivet the pin to its bar.

Bars 10 and 11 each carry a pair of depending guide pins 15 and 16 which guide pins are adapted to pass through suitable openings provided in the printing bed D. The guide pins 15 and 16 are preferably so small that the openings necessary for them do not injure the printing bed when it is used for the purpose of supporting a gelatin band wider than the distance between the bars 10 and 11.

Suitable sleeves 17 and 18 secured to a bottom plate 19 of the printing bed serve as guides for pins 15 and 16. It is to be understood that bars 10 and 11 may be lifted off merely by pulling them upward until the pins 15 and 16 on each bar are removed from the printing bed. This leaves the printing bed free of any obstructions due to the attachment. The openings necessary for the pins do not cause any harm.

Means are provided for elevating the bars 10 and 11 above the printing bed for the purpose of applying master sheet strips thereto so that the strips will not contact the gelatin band and get stuck to it while they are being assembled upon the bars 10 and 11.

The means consist of a frame 20 and four cams 21, 22, 23 and 24. The frame 20 is slidably secured to a pair of channel bars 25 and 26 which run transversely of the machine beneath the printing bed D. The frame 20 has slots 27, 28, 55

29 and 30 through which suitable bolts 31, 32, 33 and 34 extend. These bolts are clamped to the lower flanges of the angle bars 25 and 26 by suitable nuts and the bolts are provided with enlarged flat heads 35 and 36 to support the frame 20.

It will be noted from an inspection of Figs. 2 and 4 that the rear heads 35 have flat edges facing toward the rear while the front heads 36 have flat edges facing toward the front. The heads are merely cut off in this fashion in order to provide a slightly greater clearance for screws such as 37 which hold the cam members 21, 22, 23 and 24 to the frame 20.

15 Front cam members 23 and 24 are cut away as indicated at 38 in Fig. 2 so that, when the frame is in its rearmost position, they will not strike the nuts on bolts 33 and 34.

At the forward end of the machine, frame 20 has outwardly extending portions 39 and 40 which have projections 41 and 42 projecting toward the front end of the machine so as to be in the clear and accessible for an operator to grasp. These projections 41 and 42 are additionally supported by a pair of lugs 49 and 50 on the side frame members of the machine, and have suitable heads or handles 43 and 44 thereon. As shown best in Fig. 3, the handles 43 and 44 lie sufficiently far enough apart to permit the use of a much wider band of gelatin than that normally used with the bars 10 and 11.

As shown best in Fig. 5, the carriage C has a platen roller 45 which is cut out as indicated at 46 so as to clear the bars 10 and 11 (only one bar and one cut out portion are shown in Fig. 5, but it is to be understood that the same provision is made for the other bar). The bars when in lowered position are low enough to clear the carriage frame so that the carriage may be rolled over master sheet strips held by the bars 10 and 11.

10 and 11. The manner in which the device is operated is substantially as follows: Assuming that the operator desires to make up a composite master upon the duplicating band F, he first places the bar 10 and bar 11 in position on the opposite sides of the duplicating band by inserting their pins 15 and 16 in the apertures provided in the printing bed for this purpose. He then grasps the handles 43 and 44 and pulls them forward thus causing the cam members 21, 22, 23 and 24 to move the pins such as 15 and 16 upwardly to raise bars 10 and 11 into the dotted line position shown in Fig. 2.

The bars 10 and 11 in their raised positions are sufficiently spaced from the duplicating band F that an operator can readily place a plurality of strips such as 47 and 48 upon the pins 12 without the strips contacting the surface of the gelatin band F to which they would stick owing to the tackiness of the band.

When the strips have been assembled in their proper positions upon the bars 10 and 11, frame 20 is moved to the left as shown in the drawings. This movement of the frame 20 moves the cams 21, 22, 23 and 24 so as to permit the bars 10 and 11 to drop down upon the printing bed D. Carriage C may now be brought back to home position and utilized to press the master sheet strips 47 and 48 down upon the gelatin band. The strips may then be removed by lifting either of the bars 10 or 11 or both of them and copies may be made in the usual fashion. When it is unnecessary to have the bars 10 and 11 for as-

sembling master sheets, they may be lifted off and laid aside leaving the machine free for use of wider duplicating bands in the making of wider copies.

While certain embodiments of the invention have been shown and described, it will be understood that it is capable of many modifications. Changes, therefore, in the construction and arrangement may be made without departing from the spirit and scope of the invention as disclosed in the appended claims in which it is the intention to claim all novelty inherent in the invention as broadly as permissible in view of the prior art.

The invention having thus been described what we claim as new and desire to secure by Letters Patent is:

1. In a duplicating machine having a printing bed and a duplicating band thereon, a master sheet assembling attachment for said machine comprising a pair of bars on said printing bed, said bars having spaced mounting pins thereon and means for elevating said bars above the printing bed.

2. In a duplicating machine having a printing bed and a duplicating band thereon, a master sheet assembling attachment for said machine comprising a pair of bars on said printing bed, said bars having spaced mounting pins thereon and means for elevating said bars above the printing bed, said bars being removable from said printing bed.

3. In a duplicating machine having a printing bed and a duplicating band thereon, a master sheet assembling attachment for said machine comprising a pair of bars on said printing bed, said bars having spaced mounting pins thereon and means for elevating said bars above the printing bed, said last named means comprising cam means beneath the printing bed and pins extending from said bars to the cam means.

4. In a duplicating machine having a printing bed and a duplicating band thereon, a master sheet assembling attachment for said machine comprising a pair of bars on said printing bed, said bars having spaced mounting pins thereon and means for elevating said bars above the printing bed, said last named means comprising cam means beneath the printing bed and pins extending from said bars to the cam means, and a frame slidably mounted in the machine upon which said cam means are mounted.

5. In a duplicating machine having a printing bed and a duplicating surface thereon, a sheet assembling means for said machine comprising a pair of spaced members at opposite sides of said surface, said members having parallel rows of mounting pins thereon for mounting master record strips across said surface.

6. In a duplicating machine having a printing bed and a duplicating surface thereon, a sheet assembling means for said machine comprising a pair of spaced members at opposite sides of said surface, said members having parallel rows of mounting pins thereon for mounting master record strips across said surface, and means for raising and lowering said means with respect to said duplicating surface.

7. In a duplicating machine having a printing bed and a duplicating surface thereon, a sheet assembling means for said machine comprising a pair of spaced members at opposite sides of said surface, said members having parallel rows of mounting pins thereon for mounting master record strips across said surface, and means for

raising and lowering said means with respect to said duplicating surface, said last named means comprising pins passing through the printing bed for raising said members and means beneath the printing bed to move said pins up to lift said members above the printing bed.

8. In a duplicating machine having a printing bed, means to facilitate assembly of strips of master records and the like thereon comprising a pair of rows of spaced pins on which the strips may be assembled, and means mounting said rows of pins for vertical movement with respect to said printing bed.

9. In a duplicating machine having a printing bed, means to facilitate assembly of strips of master records and the like thereon comprising a pair of rows of spaced pins on which the strips may be assembled, said rows of pins being removably mounted on the bed.

10. In a duplicating machine having a printing bed, means to facilitate assembly of strips of master records and the like thereon comprising a pair of rows of spaced pins on which the strips may be assembled, means carrying said rows of pins, said last named means being movable with respect to the printing bed to raise and lower the rows of pins with respect to the printing bed.

11. In a duplicating machine having a printing bed, means to facilitate assembly of strips of master records and the like thereon comprising a pair of rows of spaced pins on which the strips may be assembled, and means mounting said rows of pins for vertical movement with respect to said printing bed, and cam means beneath said printing bed engaging said mounting means to raise the rows of pins.

12. In a duplicating machine having a printing bed and a duplicating band thereon, a master

sheet assembling attachment for said machine comprising a pair of bars on said printing bed, said bars having spaced mounting pins thereon and means for elevating said bars above the printing bed, said last named means comprising cam means beneath the printing bed and pins extending from said bars to the cam means, and a frame slidably mounted in the machine upon which said cam means are mounted, said frame having operating means projecting beyond said printing bed at one end thereof.

13. A duplicating machine comprising a frame, a printing bed thereon, a carriage movable over said bed and having a platen roller, means carrying parallel rows of spaced pins at opposite sides of said bed, said platen roller having portions of reduced diameter spaced to pass over said rows of pins in movement of the carriage over the printing bed, and manually operable means to elevate said rows of pins from the printing bed.

14. A duplicating machine comprising a frame, a printing bed thereon, a carriage movable over said bed and having a platen roller, means carrying parallel rows of spaced pins at opposite sides of said bed, said platen roller having portions of reduced diameter spaced to pass over said rows of pins in movement of the carriage over the printing bed, and manually operable means to elevate said rows of pins from the printing bed, said last named means including mechanism, mounted beneath the printing bed and elements passing through the printing bed to transmit movement from said mechanism to said pin carrying means.
